UNITED STATES PATENT OFFICE.

PATRICK J. MOLONEY, OF SAN FRANCISCO, CALIFORNIA.

RECEIVING LOOP.

Application filed March 22, 1927. Serial No. 177,327.

My invention relates to improvements in receiving loops for radio sets wherein a plurality of conductors operate in conjunction with a tube for holding said conductors in various positions to increase the selectivity of a radio set connected thereto.

The primary object of the present invention is to provide a new and improved receiving loop for radio receiving sets.

Another object is to provide a new and improved device of the character described having conductors extending in a multiplicity of various directions to more readily intercept lines of radio transmission and thereby increase the selectivity of the set without turning or manipulating said loop, thereby decreasing the number of manipulations required by an operator of a receiving set in selecting a station and leaving him free to concentrate his attention on other adjustments.

A further object is to provide a new and improved receiving loop for radio receiving sets having a plurality of radially disposed semi-circular conductors detachably connected to a tube to facilitate assembly and manufacture of said loop.

A still further object is to provide a new and improved device of the character set forth composed of a few parts easily assembled and possessing a maximum efficiency.

I accomplish these and other objects by means of the device disclosed in the present application, wherein like characters of reference are used to designate similar parts throughout the said application and drawings, and in which,

Fig. 1 is a plan view, partly broken, disclosing my improved receiving loop;

Fig. 2 is a side elevation of Fig. 1;

Fig. 3 is an enlarged broken detailed view partly in section, disclosing the manner in which the conductors are detachably mounted;

Fig. 4 is a slightly enlarged plan view of one end of the tube with the conductors removed, disclosing the slots; and

Fig. 5 is a slightly enlarged broken view of one end of the tube, partly in section.

Referring to the drawings, the numeral 1 is used to designate a vertically disposed tube having open upper and lower ends provided with preferably equally spaced slots 2 and an annular beveled portion 3 within each end thereof extending inter-

nally or inwardly from the inner ends of the slots 2. The internal portion of the tube 1 is provided with an internally threaded portion 4 at each end thereof and directly inside of the slotted ends or portions of said tube 1, as disclosed in Figs. 3 and 5 of the drawings.

A collar 5 is threaded to screw into either end of the internally threaded ends of the tube 1 and is likewise provided with an annular beveled portion 6 arranged to match or contact with the adjacent annular beveled portion 3 of the tube 1.

A plurality of semi-circular conductors 7 of suitable material, having their opposite ends projected through the slots 2 in opposite ends of the tube 1 and also slightly beyond the beveled portions 3 thereof, the projected lower ends of said conductors 7 being somewhat longer than the upper ends in order that said lower ends may be twisted or otherwise united to form a single conductor 8 leading to the receiving set, not shown.

In order to facilitate assembly and proper contact of the conductors with the tube 1, without soldering, the collars 5 are screw threaded into each end of the tube 1 until the beveled annular surfaces or portions 6 thereof engage the respective projected ends of the semi-circular conductors 7 and press them tightly against the annular beveled portions 3 of the tube 1 thereby assuring a proper contact and conductivity of the said conductors 7.

As the slots 2 of the tube 1 within which the opposite ends of the conductors 7 are projected are equally spaced the said conductors 7 will be radially disposed and present or from a loop having conductors for the interception of radio transmission waves, extending in a multiplicity of directions thereby increasing the selectivity of the loop thus formed.

The tube may be suspended or supported in any suitable manner.

Having thus described my invention what I claim as new and desire to secure by Letters Patent is:

1. A receiving loop for radio receiving sets comprising a tube having a plurality of longitudinally disposed slots cut into each end of said tube and likewise having an annular beveled surface on the inside of said tube adjacent each end thereof and adjacent said slots; a plurality of semi-circular and radially disposed conductors having their oppo-

site ends mounted within said slots in the opposite ends of said tube and projecting into the interior of the same; and means for maintaining contact of the ends of said conductors with the beveled surfaces of said tube.

2. A receiving loop for radio receiving sets comprising a tube have a plurality of longitudinally disposed slots in each end of said tube and also having an annular beveled surface on the inside of each tube and within the inner ends of the slots therein; a plurality of radially disposed semi-circular con-

ductors having their opposite ends mounted within said slots in opposite ends of said tube and projecting into said tube; and an annular collar screw-threaded into each end of said tube and having a beveled surface arranged to engage the inwardly projecting ends of the conductors and to hold the same in contact with the annular beveled surface of the tube. 15 20

In witness whereof I hereunto set my signature.

PATRICK J. MOLONEY.
